UNITED STATES PATENT OFFICE.

HAROLD W. BUCK, OF NEW YORK, AND EDWARD M. HEWLETT, OF SCHENECTADY, NEW YORK,
ASSIGNORS TO GENERAL ELECTRIC COMPANY, A CORPORATION OF NEW YORK.

SUSPENSION OF HIGH-TENSION LINES.

No. 825,561.

Specification of Letters Patent.

Patented June 22, 1909.

Application filed October 31, 1907. Serial No. 400,125.

To all whom it may concern:

Be it known that we, HAROLD W BUCK and EDWARD M. HEWLETT, citizens of the United States, residing, respectively, at New York, county of New York, State of New York, and at Schenectady, county of Schenectady, State of New York, have invented certain new and useful Improvements in Suspension of High-Tension Lines, of which the following is a specification.

The present invention relates to overhead suspension of electric conductors and more especially to conductors of power circuits of high potentials from 60,000 to 100,000 volts.

Heretofore it has been the standard practice to provide the poles or cross arms with pins upon which were placed vertical insulators to which the conductors were directly and rigidly attached. These insulators, in order to adapt them for use with high potential circuits, were made up by superposing a plurality of petticoats one above the other, the number of such petticoats varying with the voltages of the currents, and accordingly the insulators for use with high potential circuits were necessarily of large dimensions, the dimensions varying with the cube of the potential above 60,000 volts. Besides being expensive, these old forms of insulators were objectionable on account of the leverage strains which any side motion of the conductor imposed thereon. Moreover, when exposed to heavy rain, the flow of water from one petticoat to the next provided a low resistance path for the current between the conductor and tower. Where the conductor wire is rigidly attached to the insulator, as has been the practice heretofore, it soon becomes crystallized near the point of attachment due to the swaying of the conductor span under the influence of the wind. Furthermore it has been the practice to support a conductor in short spans in order to relieve the insulators of the excessive leverage strains, and as a consequence a large number of expensive poles or towers have been necessary.

The object of this invention is to provide a system of suspension whereby a high potential conductor may be effectually and reliably supported and insulated at a reasonable cost.

In carrying out our invention, we do away with the usual insulators and their pins and provide at certain of the supporting towers a vertical series of insulators flexibly connected

to each other and attached by a hooked joint at the upper end to the under side of a cross arm of the tower and at the lower end by an ear or other suitable connection to the suspended conductors. At certain other towers the conductor is dead ended through a horizontal series of flexibly connected insulators on each side of the cross arm and a jumper connection joins the dead ends of the conductor and hangs freely by gravity below the cross arm. The dead ending of the conductor will occur at angles in the conductor in order to take the side stress due to change in direction thereof, and is preferably used at least at every fourth or fifth tower on tangents or straight sections in order to prevent longitudinal waves of the conductor due to wind. The dead ended arrangement may be employed at all points of suspension where preferred, but the construction illustrated herein has advantages.

For a more complete understanding of our invention, reference may be had to the following detailed description and the accompanying drawing forming a part of this specification, in which—

Figure 1 is a perspective view showing three conducting wires and the upper portion of two supporting towers, the conductors being dead ended at the left-hand tower and carried by vertical series of insulators at the right-hand tower; Fig. 2 shows on a larger scale a vertical series of insulators; and Fig. 3 is a similar view of a horizontal series of insulators.

The towers are preferably made of iron on account of their greater permanence, strength and facility of transportation. As shown in the drawing, they carry at their tops or near their tops horizontal cross arms secured by suitable means 2 to the main struts 3, and to each of the cross arms 1 are connected iron rings 4 near the ends and middle thereof, each ring being provided with one or more eyes 5 according as they are designed to receive vertical insulator connections as shown at the right-hand tower, Fig. 1, or dead end insulator connections as shown at the left-hand tower.

The conductor wires 6 are shown at the right-hand tower, Fig. 1, provided with ears 7 having eyes 8 at their upper edges through which flexible bands or cables 9 are threaded. At the upper ends of the band 9 is a link insulator 10 through which the band is thread-

ed, and above the insulator 10 is a second band or cable 11 connecting the first link insulator 10 with the second link insulator 12, and at the upper side of link insulator 12 is 5 another band or cable 13 threaded there-through and having at its upper portion a hook 14 adapted to engage an eye 5 carried by the cross arm 1. While only two link insulators 10 and 12 are shown, it is to be un- 10 derstood that any desired number may be connected in series to provide for any voltage. This vertical arrangement permits a great 15 freedom of movement of the conductors with the conductor wire at its point of suspension, and crystallization of its metal is thereby entirely prevented. Moreover, by reason of the iron towers projecting above the level of the wires, any lightning disturbances will be 20 transmitted to ground through the towers and will not be taken by the conductor wires.

In the dead ended arrangement shown at the left-hand tower of Fig. 1, the conductor wires 6 are provided with clamps 15 adapted to receive the tension of the wires and pro- 25 vided with an aperture through which flexible bands or cables 16 are threaded and by which the adjacent insulator 17 is flexibly connected therewith. A second flexible band or insulator 18 connects link insulator 30 17 with link insulator 18' and a third flexible band or cable 19 connects the link insulator 18 with a hook 20 which is adapted to engage one of the eyes 5 carried by the cross arm of the tower. This arrangement is duplicated 35 on the opposite side of the cross arm to dead end the opposite span, and a jumper connection 21, which may be either a continuation of the conductor wire 6 or an independent wire, extends from the clamp 15 on one side 40 of the cross arm to the corresponding clamp on the other side and hangs freely by gravity beneath the cross arm. This dead ended arrangement is such that a longitudinal movement of a wire under the wave action pro- 45 duced by the wind is effectually resisted. Also any horizontal stress due to the angularity in the course of the wire is provided for.

Each of the vertical link insulators 10 and 12, as shown in detail in Fig. 2, consists of a 50 disk portion 22 having its center enlarged and provided with interlinking portions 23 and 24 with a solid wall of insulation between them, so that when the flexible bands or cables 9, 11 and 13 are threaded there- 55 through, the current cannot pass from one to the other without actual puncturing of the insulating material. The lower surface of the insulator has an outwardly flaring flange 25 which acts to increase the creepage sur- 60 face and maintains the main portion of the lower disk surface dry. The flexible bands or cables have their free ends joined by suitable clamps 26. The horizontal link insulators, as shown in Fig. 3, have a disk 65 portion 22 with an enlarged central portion

through which they extend from opposite directions to curved apertures 23 and 24 which interlink and have a solid wall of insulation between them, and at the periphery of the disk are two oppositely flaring flanges 70 26 whereby the peripheral trough is formed by their outer surfaces. This arrangement is such that from whichever direction the rain strikes the insulator, it will be deflected from the sheltered side so that the latter will 75 remain dry and the liability of the current to pass thereover will effectually be prevented. It will therefore be seen that by reason of the interlocking of the several insulators into a series or chain any potential can be 80 carried thereby in safety. If by reason of structural or electrical weakness of any insulating unit, one or more insulator walls should break down, the efficiency of transmission remains unimpaired since the inter-linked metal loops hold the line almost as taut as before. If a suspension insulator should be punctured through electrical weakness or by reason of mechanical blows or damage, the other insulators of the chain 90 85 will remain intact; or if by an extraordinary conjunction of unfavorable conditions insulators should be destroyed still the line remains suspended, and the current is harmlessly grounded, opening the circuit in the usual way at the station switches under the abnormal load condition.

We do not desire to restrict ourselves to the particular form of construction or arrangement of parts herein shown and described, since it is apparent that they may be changed and modified without departing from our invention.

What we claim as new and desire to secure by Letters Patent of the United States, is,— 105

1. In a system of high tension line suspension, the combination of periodically dead ended spans joined by jumper connections, and intervening spans freely suspended beneath cross arms of the supporting towers. 110

2. In a system of suspension for high tension power circuits, the combination of conductor spans dead ended at the cross arm through two chains of insulators flexibly connected to each other and to the cross arm, and a jumper connection between the adjacent ends of the spans and hanging freely by gravity beneath the cross arm. 115

3. In a system of high tension line suspension, the combination of periodic spans dead ended on opposite sides of a cross arm or support through series of insulators flexibly connected and electrically connected by depending jumper wires, and intervening spans freely suspended beneath cross arms of the 120 respective supporting towers.

4. In a system of high tension line suspension, the combination of spans each dead ended to its cross arm through series of flexibly connected insulators, each series of con- 125 130

nected insulators having flexible connection with the supporting cross arm.

5. In a system of suspension for high tension power circuits, the combination of a series of flexibly connected link strain insulators between line wire and cross arm, the number of said insulators being proportioned to the electrical potential, and each insulator being provided with a rain shed to preserve 10 dry some part of its surface in the path of possible electric discharge irrespective of the direction of the beating rain, and means for flexibly connecting said series of insulators to the cross arm and to the line wire.
- 15 6. In a system of high tension line suspension, the combination of towers provided with cross arms, of conductor spans freely suspended beneath said cross arms by series of flexibly connected disk insulators.
- 20 7. A high potential power transmission line having at intervals between its terminals a chain of insulators, each unit of which is mechanically interlinked with the adjacent one and the terminal units secured to the 25 line, metallic jumper connections around each chain to complete the metallic conti-

nuity of the line, and a chain of similarly interlinked insulators at the points of support for the purpose described.

8. A high potential power transmission line having at intervals between its terminals a chain of insulators, each unit of which is mechanically interlinked with the adjacent one, and a chain of similarly interlinked insulators at the several points of support, 30 each insulator unit being provided with a rain shed to preserve dry some part of its surface in the path of possible electric discharge, irrespective of the direction of beating rain.

35 In witness whereof, BUCK has hereunto set his hand this 26 day of October, 1907, and HEWLETT has hereunto set his hand this 29th day of October, 1907.
